CLAIM

The ornamental design for a tube coupler, substantially as shown and described.

DESCRIPTION

FIG. 1 is a perspective view taken from the top, one side and one end of a tube coupler showing our new design;

FIG. 2 is an elevational view taken at a 45° angle from the top shown in FIG. 1;

FIG. 3 is a top plan view thereof;

FIG. 4 is a side elevational view thereof, the opposite side being a mirror image of the side shown;

FIG. 5 is a bottom plan view thereof;

FIG. 6 is an elevational view taken 180° from the view shown in FIG. 2;

FIG. 7 is a perspective view taken from the top, one side and one end of a modified form of the tube coupler shown in FIG. 1;

FIG. 8 is a top plan view of FIG. 7;

FIG. 9 is a side elevational view of FIG. 7, the opposite side being the same as the side shown;

FIG. 10 is an end elevational view of FIG. 7, the opposite end being the same as the end shown;

FIG. 11 is a bottom plan view of FIG. 7;

FIG. 12 is a perspective view taken from the top, one side and one end of a second modified form of the tube coupler shown in FIG. 1;

FIG. 13 is a top plan view of FIG. 12, the bottom being the same as the top shown;

FIG. 14 is a side elevational view of FIG. 12, the opposite side being the same as the side shown; and,

FIG. 15 is an end elevational view of FIG. 12, the opposite end being the same as the end shown.

Fig. 1.Fig. 3.Fig. 2.Fig. 4.Fig. 5.Fig. 6.

Fig. 7.Fig. 8.Fig. 9.Fig. 10.Fig. 11.

Fig. 12.

Fig. 13.

Fig. 14.
